FUEL PUMP GOVERNOR

Richard Joseph Ifield, Ealing, London, England,
assignor to Joseph Lucas Limited, Birmingham,
England

Application November 15, 1944, Serial No. 563,587
In Great Britain October 15, 1942

2 Claims. (Cl. 121—38)

1

This invention relates to the governing means employed for automatically controlling the output of a variable-delivery fuel pump used in conjunction with prime movers, the governing means being responsive to variable fluid pressure conditions. In particular the invention relates to a governing means consisting of a spring loaded piston or diaphragm adapted to actuate the output controlling means of the pump, the piston or diaphragm being contained in a chamber. The piston (which term will hereafter be used as including also a diaphragm) is subject on both sides to the action of fluid pressure. Means are provided for effecting an unrestricted pressure-fluid supply to one side of the piston, and this fluid can also gain access to the other side through a restricted passage so that pressure differences can occur temporarily for actuating the piston, the pressures at the two sides being equal during a steady pressure condition in the system. At the side of the chamber opposite to that which receives the unrestricted fluid supply there is provided a release valve which is responsive to any predetermined condition associated with the system, such as the speed of the pump. Governing means as above described are hereinafter referred to as of the kind specified.

The above described governing means possesses the disadvantages that undesired pressure or volume fluctuations may be set up in the liquid delivered by the pump, and the object of the present invention is to enable this condition to be minimised in a simple and satisfactory manner.

The invention comprises the combination with a governing means as above described, of a variable-volume chamber arranged in communication with the valve-controlled side of the piston chamber, the variable-volume chamber being such that it permits movement of the piston in response to a pressure change independently of the valve.

In the accompanying sheet of explanatory drawings:

Figure 1 is a diagrammatic sectional elevation of a liquid fuel pump embodying the invention.

Figure 2 is a fragmentary sectional side view illustrating a modified form of the invention.

The liquid fuel pump shown in the drawing comprises a rotary body part *a* arranged in a casing *b* and having formed around its axis a plurality of bores as *c* in each of which is arranged a reciprocating plunger *d*. The body part *a* is adapted to be driven in any convenient manner by the prime mover to be supplied with liquid fuel from the pump. During rotation of the body

2

part *a* the plungers *d* are moved in one direction by an angularly movable swash plate *e* and in the opposite direction by springs as *f*, the latter being situated in the bores *c*, and serving to hold an end face of the body part in contact with a flat seating *g* in the casing *b*. The swash plate *e* is of annular form, and is pivoted at diametrically opposite positions to the casing *b*. The seating *g* is formed with a port *h* communicating with a liquid inlet *i* in the casing *b* and with another port *j* communicating with a liquid outlet *k* in the casing.

The body part *a* is adapted to serve also as a centrifugal pump, and for this purpose is formed with an axial bore *m* which at one end communicates with the inlet *i* through another port *n* in the seating *g*, and at the other end communicates with a plurality of radial passages as *o* in the body part. Liquid from the inlet *i* flows through the bore *m* and is expelled by centrifugal action through the radial passages *o* into the interior of the pump casing *b* around the body part *a*.

In one end of the casing *b* is formed a cylindrical chamber *p* having closed ends. Within the chamber *p* is arranged a piston *q* loaded by a spring *r*, and extending from one side of this piston and through a bore in the casing *b* at the inner end of the chamber is a rod *s* connected to the swash plate *e*. Instead of the piston a diaphragm may be employed, and as already stated I desire this alternative to be included in the term piston. The inner portion of the chamber *p*, that is the portion at the piston rod side of the piston *q*, is in free communication with the outlet *k* through a passage *l* in the casing *b*, and this portion of the chamber also communicates with the other or outer portion of the chamber (which contains the spring *r*) through a restricted passage *t*. The outer end of the chamber *p* is provided with a vent *u* which at its outer end forms a seating for a valve *v*, this latter being responsive to any predetermined condition associated with the system.

45 In the example shown the valve *v* is formed or secured on one end of a lever *w*, the latter being pivoted at a position between its ends on the outer end of the chamber *p*, and being loaded by a spring *x* which tends to hold the valve on its seating. The lever *w* is contained in a chamber *y* formed on or secured to the adjacent end of the casing *b*, and this chamber communicates with the pump inlet *i*. The outer side of the chamber *y* is bounded by a controlling diaphragm *z* having at its centre an abutment *2* which is adapted to

bear on the end of the lever w remote from the valve v . At the outer side of and bounded in part by the diaphragm z is another chamber 3 , this latter being in communication with the above mentioned centrifugal pump through a passage 4 in the casing b . Also the diaphragm z is loaded by a spring 5 connected to an adjusting member 6 , the latter being operable in any convenient manner by an attendant to vary the effect of the spring.

Assuming the swash plate e to be in a position of maximum obliquity, that is to say the position in which the pump gives its maximum output, the swash plate will remain in this position so long as the pressure in the chamber 3 (and thus acting on the controlling diaphragm z) is below some predetermined amount. In this condition the valve v is in its closed position and the liquid pressures at the two sides of the piston q are equal. But when the pressure acting on the diaphragm z exceeds the predetermined amount the diaphragm will move the valve v off its seating. The liquid pressure in the outer portion of the piston chamber p will now fall and the piston q will be moved by the fluid pressure in the inner portion of the cylinder against the action of the spring r , so moving the swash plate e in the direction for reducing the pump output until a new condition of equilibrium is reached. If the valve v subsequently moves on to its seating as a result of the pressure on the diaphragm z falling below the predetermined amount, the liquid pressures at the two sides of the piston q again become equal, and the spring r then serves to move the piston in the direction for increasing the pump output.

From the foregoing it will be seen that as the position of the swash plate e is dependent on the pressure of the liquid in the chamber 3 and as this pressure is dependent on the speed of the pump, the latter is governed by the speed of the prime mover which drives the pump.

In carrying the invention into effect as shown in Figure 1, I connect the valve-controlled outer end of the chamber p by means of a passage 7 to one end of a small variable-volume chamber 9 containing a spring loaded piston 10 which controls the volume of the latter chamber, the other end of this chamber being in communication with the outer atmosphere through a vent 11 . Under a steady condition in the system the piston q of the governing means remains at rest. But when a variation (rise or fall) of fluid pressure occurs at a sufficient rate the piston q can move in the appropriate direction in immediate response to the change and independently of consequential movement of the valve v , as liquid can now flow between the chamber p of the governing means and the additional chamber 9 of variable volume. This liquid flow permits movement of the piston q of the governing means in response to pressure fluctuations which are too brief to permit movement of this piston under the control of the valve v . It will be understood that when a pressure rise occurs at a sufficient rate liquid flows from the chamber p to the chamber 9 , this being permitted by movement of the piston 10 against the action of its spring loading, and if this pressure rise persists the valve v will be moved away from its seating, allowing return flow of liquid from the chamber 9 to the chamber p .

Likewise, if a pressure fall occurs at a sufficient rate liquid flows from the chamber 9 to the chamber p under the action of the spring loaded piston 10 , and subsequently returns either in response to a pressure rise or to pressure liquid supplied to the end of the chamber p communicating with the chamber 9 .

In the example shown in Figure 2, the passage 7 interconnecting the chambers p and 9 is controlled by a spring loaded valve 12 which permits free flow of liquid from the chamber p to the chamber 9 but restricts the return flow. In other respects this example is similar to that shown in Figure 1 with the exception that the restriction in the passage t interconnecting the ends of the chamber p is effected by a plug 13 , sufficient clearance being provided between the plug and passage to allow a restricted flow of liquid through the passage.

By this invention the above mentioned disadvantage of the earlier form of governing means is effectively avoided.

This invention is not, however, limited to the particular examples described as constructional details may be varied to suit different requirements. Thus instead of the piston-controlled variable-volume chamber above described I may employ a chamber provided with a diaphragm and this may be loaded either by a spring or by gas under pressure; or I may employ an extensible closed chamber constructed from flexible material, for example, corrugated sheet metal.

Having thus described my invention what I claim as new and desire to secure by Letters Patent is:

1. Governing means of the kind specified, having in combination a fluid pressure responsive member, a main chamber containing said member, a passage for admitting an unrestricted supply of pressure fluid to said main chamber at one side of said member, a restricted passage for admitting pressure fluid to said main chamber at the other side of said member, a pressure-fluid release valve situated at the side of said main chamber to which pressure fluid is admitted through said restricted passage, and a variable-volume chamber arranged in communication with the release valve side of said main chamber to permit movement of said member in response to a pressure change independently of said valve.

2. Governing means of the kind specified, having in combination a fluid pressure responsive member, a main chamber containing said member, a passage for admitting an unrestricted supply of pressure fluid to said main chamber at one side of said member, a restricted passage for admitting pressure fluid to said main chamber at the other side of said member, a pressure-fluid release valve situated at the side of said chamber to which pressure fluid is admitted through said restricted passage, a variable-volume chamber arranged in communication with the release valve side of said main chamber to permit movement of said member in response to a pressure change independently of said valve, and a second valve arranged between said main chamber and said variable-volume chamber, said second valve serving to permit free flow of liquid from said main chamber to said variable-volume chamber, but to restrict flow in the opposite direction.
